UNITED STATES PATENT OFFICE.

HAROLD ROWNTREE, OF SCARSDALE, NEW YORK, AND ROSCOE D. CONKLIN, OF Rahway, New Jersey, assignors to NATIONAL PNEUMATIC COMPANY, OF NEW YORK, N. Y., A CORPORATION OF WEST VIRGINIA.

SYSTEM FOR OPERATING THE EXIT AND TRAP DOORS OF RAILWAY COACHES.

Application filed May 23, 1925. Serial No. 32,313.

This invention relates to railway coaches of the character described provided with the usual steps normally covered by a hinged trap door flush with the platform and which 5 platform is closed by an exit door. When such a car stops to take on or discharge passengers from a low level platform steps are required and accordingly the exit door is not only opened, but the trap door is lifted 10 to allow free access to the steps. When the car stops, however, at a high level platform, i. e., one which is at substantially the same elevation as the top of the trap door, the steps are not required and although the exit 15 door must be opened, the trap door remains down.

The object of the present invention is to provide a system whereby the operations of the doors may be controlled by the motorman, but wherein the operation of the trap door is automatically controlled by the presence or absence of a high level platform. That is to say, it is the object of this 20 invention to provide a construction wherein the manual operation of a control valve will serve to open only those doors which are necessary, dependent upon the particular type 25 of platform, in juxtaposition with which, the car is standing. For example, if the car is at rest adjacent a high level platform, the exit door alone should be operated while, in the case of a low level platform, both 30 doors should be actuated.

A further object of the invention is to 35 provide certain safety features which will preclude the operation of the doors, in the event some one is in a position to be injured through such operation.

Another feature of the invention resides 40 in means for controlling the operation of the doors in predetermined sequence, so that the exit door may be opened prior to the raising of the trap door and closed subsequent to the lowering of the trap door.

In the preferred manner of carrying out 45 the present invention, both the exit and trap doors are operated by pneumatic engines which are primarily controlled by a suitable control valve preferably operable 50 by the conductor, motorman or guard and the engine of one door is further controlled by the engine of the other door, to the end that the exit door must be fully opened before the engine of the trap door is per-

mitted to come into operation, and the trap 55 door must be fully closed before the engine of the exit door can come into operation to close its door. The interaction between these engines may be purely pneumatic, purely 60 electric, or may be electropneumatic, if desired.

In the preferred embodiment of the invention, the operation of the trap door may be conveniently controlled by means of a 65 mechanical feeler carried by the car and adapted, in turn, to be controlled by a high level platform so that if such a platform is present, the trap door will be precluded from operation, while if absent, operation of the trap door will result at the completion of 70 the operation of the opening of the exit door. This arrangement brings about an automatic control of the trap door, causing the door to be raised when the car is adjacent a low level platform and it is in lowered 75 position when the car is adjacent a high level platform.

Features of the invention, other than those adverted to, will be apparent from the hereinafter detailed description and claims, 80 when read in conjunction with the accompanying drawings.

The invention consists substantially in the construction, combination, location and relative arrangement of parts, all as will be 85 more fully hereinafter set forth, as shown by the accompanying drawings and finally pointed out in the appended claims.

Figure 1 is a side elevation of one end 90 of a railway coach, showing the present invention associated therewith.

Figure 2 is an end elevation of the coach shown in Figure 1.

Figure 3 is a fragmental plan view showing the relationship of the exit door operating engine to the door which it operates. 95

Figure 4 is a diagrammatic layout illustrating the preferred form of the complete system of the present invention; and,

Figure 5 illustrates a slightly modified 100 form of construction.

Referring to the drawings, 1 designates the exit door and 2 the trap door associated with one side of the platform at one end of a car. The exit door is mounted on and 105 carried by a vertical shaft 3 through rotation of which the exit door may be swung from open to closed position and vice versa.

The trap door 2 is mounted on a horizontal shaft 4 carried in bearings 5 and on which shaft, as a pivot, the trap door may be swung up or down as may be required.

5 When the trap door is in lowered position it lies in a horizontal plane with its upper surface flush with the vestibule platform 6 of the car.

With the exit door is associated an operating engine 7 which, as best shown in Figure 3, is connected by a link 8 to an arm 9, secured to the vertical shaft 3, so that through the operation of the engine 7, the shaft may be oscillated to open or close the 15 door.

A pneumatic engine 10 is provided to operate the trap door 2 and this engine is connected by means of a link 11 to an arm 12, rigid with the shaft 4, shown best in 20 Figure 1. The engines are controlled, primarily, from a control valve 13, shown best in Figure 4.

14 designates the car steps by way of which passengers are adapted to pass from 25 the vestibule platform of the car to a low level platform, and vice versa. These steps, which have heretofore been made rigid with the car frame are, in accordance with the present invention, pivoted at 15, as shown 30 best in Figure 4, and are held in normal position by a spring 16, one end of which bears against a rigid stop 17 and the other end of which bears against a bracket 18 carried by the steps. A bolt or stop as shown 35 at 18^A may be used if desired, which will be operated by the trap door to prevent the steps oscillating during the motion of the train, by holding the steps rigid when the trap door is down, but this stop is retracted 40 when the trap door is raised so as to permit the steps to slightly yield when the weight of a person is imposed thereon.

19 designates what may be graphically termed a feeler. This feeler comprises a 45 cylinder mounted rigidly on the car and in which cylinder is positioned a piston 20 (Fig. 4) having a stem 21, which projects through one end of the cylinder and in a lateral direction with reference to the car 50 and is provided at its free end with a shoe 22. The feeler is positioned at a height adapting it to cooperate with the edge of a high level platform P, but a spring 23 normally forces the piston into retracted position to withdraw the shoe 22 from engagement with the platform.

The particular structural details of the various elements to which we have referred may be varied without departing from this 60 invention which consists mainly in the manner in which these various parts are connected for interaction so that the operation of one part may control the operation of another and vice versa. To this end the 65 control valve is connected by means of a

pipe 23' to one end of the cylinder of the exit door engine (see Figure 4) and in this pipe is included a cut off valve 24. This valve is a double action valve and embodies a casing 25 in which is positioned two sealing members 26 and 27 rigid on a common stem and acted upon by a spring 28 to force the sealing member 26 normally to its seat and to unseat the sealing member 27. The stem projects to a point directly beneath the 75 trap door 2 which is normally slightly elevated by a spring 29. So long as there is no weight imposed on the trap door, the spring 29 will slightly elevate said door while the spring 28 will seat the sealing 80 member 26 so that pressure can flow from the control valve to the engine 7. If, however, a person is standing on the trap door 2 at the time the control valve is moved into a position to effect opening of the exit 85 door, the weight of such person will depress the spring 29 causing the trap door to force the valve stem down and seat the sealing member 27, so as to preclude passage of pressure to the engine 7 of the exit door. 90

If it be assumed that no one is standing on the trap door 2, then the pressure communicated to the engine 7 will cause the piston therein to move to the right in Figure 4 and as a result the exit door will be opened 95 through the conventional connections.

It will be noted, however, that after the piston has moved sufficiently to fully open the exit door, such piston will uncover the 100 pipe 30 which leads to the rear end of the feeler cylinder 19. After the exit door has been fully opened, pressure will be communicated to the feeler and will be applied to the rear end of the feeler piston 20, the shoe of which is in retracted position as shown 105 in Figure 2. If the car is at rest adjacent a high level platform, the pressure admitted to the cylinder 19 will simply force the shoe against the edge of the platform which will constitute a stop to preclude more extensive movement of the piston. If, however, the car is at rest adjacent a low level platform, the piston will be free to move to the left in Figure 4 under the pressure admitted to the rear of the cylinder for a sufficient distance to uncover a pipe 31 which leads directly to the end of the trap door operating engine 10. Pressure thus communicated to the engine 10 will effect the 110 operation of the engine with a consequent 115 lifting of the trap door.

It will thus be apparent that the feeler will automatically control the operation of the trap door. That is to say, if the car 125 stops at a high level platform where the use of steps is not necessary, the feeler will preclude the pneumatic pressure from reaching the engine of the trap door whereas if a low level platform is encountered, the feeler will allow pressure to be conveyed to the engine 130

of the trap door and said door will be raised. This control of the trap door is absolutely automatic and is primarily controlled by the presence or absence of a high level platform.

To effect the operations which we have described, it is of course necessary to move the controller valve handle 32 into the full line position of Figure 4. When it is desired to reverse these operations, for the purpose of closing such doors as have been opened, the controller valve handle 32 is moved into the dotted line position of Figure 4, whereupon the flow of fluid is as follows.

Pressure is conveyed from the valve through a pipe 33 which leads to the opposite end of the trap door engine 10 and in this pipe is included a cut off valve 34 of a construction identical with the valve 27. The stem of the cut off valve 34 extends into proximity with the bracket 18 associated with the car steps. The spring 16 normally holds the bracket free from engagement with the valve stem, but if a person is standing on the steps a spring 16 will be compressed and the valve will seal the pipe 33, so that fluid pressure cannot be fed to the engine 10. The purpose of this arrangement is to preclude the folding down of the trap door in the event that some one is standing on the steps. If this should occur the person on the steps would be very liable to injury.

If no one is standing on the steps when pressure is admitted into the pipe 33, such pressure is fed through said pipe to the engine 10 and the piston of said engine is caused to travel to the left in Figure 4, in order to effect the folding down of the trap door. After the door has been folded down and the piston of the engine 10 reaches the terminus of its travel, it uncovers a pipe 34' which leads directly to the closing end of the exit door engine 7, so that when this pipe is uncovered and pressure is fed thereto through the engine 7, the exit door is automatically closed.

In Figure 5, we have shown a construction which is very similar to the construction of Figure 4, except that instead of using check valves operated directly by the trap door and steps, the check valves are magnetically operated. In this latter showing the check valve 25^a corresponds to the check valve 25 and the check valve 34^a corresponds to the check valve 34.

The valve 25^a is magnetically operated and is included in an electric circuit 35 of which a bridge piece 36 forms a part. The bridge piece 36 is carried on, but insulated from a post 37 rigid with the trap door 2 and when the trap door is raised by the spring 29, the bridge piece is free from the

contacts with which it is adapted for co-operation. However, if weight is imposed on the trap door 2, the trap door will be depressed against the tension of the spring 29 and the bridge piece 36 will complete the circuit 35 and cause the valve 25^a to preclude the passage of fluid pressure through the pipe in which it is included. The same arrangement applies with reference to the valve 34^a. It will thus be apparent that Figure 5 differs from Figure 4 merely in that the latter figure includes the operation of the check valves electrically whereas the former figure shows them as operated directly and mechanically.

It is to be particularly noted that the arrangement of parts which we have described insures absolute safety to passengers and at the same time assures a proper synchronism or sequence in the operations of the parts, only such parts being operated as are essential to the practical conditions prevalent at the time of operation. The movement of the trap door is automatically governed by the presence or absence of a high level platform and the parts are so coupled together that the trap door cannot open unless the exit door is already opened and will close before the exit door can close. The system operates with absolute efficiency and provides complete automatic control of the parts which it is desired to operate. The motorman or guard is only required to operate the control valve, the remaining parts of the system are entirely automatic. In Figures 4 and 5 we have shown a conventional type of cushioning valves, whereby the doors are slowed up and cushioned as they approach the limit of their movement.

Therefore, having set forth the objects and nature of our invention, and having shown and described an operative structure embodying the principles thereof, what we claim as new and of our own invention, and desire to secure by Letters Patent, is:

1. In a system of the character described, the combination with a car having an exit door, steps and a trap door for normally covering the steps, of agencies for operating the said doors in predetermined sequence, manually operable means for initiating the operation of said agencies, and means for rendering said agencies irresponsible to the manually operable means while a passenger is standing on the trap door.

2. In a system of the character described, the combination with a car having an exit door, steps and a trap door for normally covering the steps, of pneumatic agencies for opening said doors in predetermined sequence, a manually operable pneumatic control valve for initiating the operation of said agencies, and a cut off valve, operable by the trap door when the weight of a pas-

- senger is imposed on said door, for rendering said agencies irresponsive to the control valve.
3. In a system of the character described, 5 the combination with a car having an exit door, steps and a trap door for normally covering the steps, of pneumatic agencies for closing the doors in predetermined sequence, a control valve for initiating the operation 10 of said agencies and a cut off valve, operable by the steps when the weight of a passenger is imposed on said steps for rendering the said agencies irresponsive to the control valve.
- 15 4. In a system of the character described, the combination with a car having an exit door, steps and a trap door for normally covering the steps, of agencies for opening and closing the doors in predetermined sequence, manually operable means for initiating the operation of said agencies to open or close the doors, means for rendering said agencies irresponsive to the manually operable means to open the doors while a passenger is standing on the trap door, and means for rendering said agencies irresponsive to the manually operable means to close the doors while a passenger is standing on the steps.
- 20 5. In a system of the character described, the combination with a car having an exit door, steps and a trap door for normally covering the steps, of pneumatic agencies for opening and closing the doors in predetermined sequence, a pneumatic control valve for initiating the operation of said agencies to open or close the doors, a cut off valve for rendering said agencies irresponsive to the control valve to open the doors 25 while a passenger is standing on the trap door, and a cut off valve for rendering said agencies irresponsive to the control valve to close the doors while a passenger is standing on the steps.
- 30 6. In a system of the character described, the combination with a car having an exit door, steps and a trap door for normally covering the steps, of agencies for opening the doors in predetermined sequence, manually operable means for initiating the operation of said agencies, and means, controlled by the proximity of a high level station platform, for rendering the operating agencies of the trap door inoperative when 35 the car is in proximity to such platform.
7. In a system of the character described, the combination with a car having an exit door, steps and a trap door for normally covering the steps, of pneumatic agencies for opening the doors in predetermined sequence, a pneumatic control valve for initiating the operation of said agencies, and means, controlled by the proximity of a high level station platform, for rendering the operating agencies of the trap door inopera- 40 tive when the car is in proximity to such platform.
8. In a system of the character described, the combination with a car having an exit door, steps and a trap door for normally covering the steps, of agencies for opening and closing the doors in predetermined sequence, manually operable means for initiating the operation of said agencies to open or close the doors, means for rendering said agencies irresponsive to the manually operable means to open the doors while a passenger is standing on the trap door, means for rendering said agencies irresponsive to the manually operable means to close the doors while a passenger is standing on the steps, and means, controlled by the proximity of a high level station platform, for rendering the operating agencies incapable of opening the trap door when the car is in proximity to such platform. 45
9. In a system of the character described, the combination with a car having an exit door, steps and a trap door for normally covering the steps, of an engine for operating the exit door, an engine for operating the trap door, connections between said engines for conveying power from one engine to the other in predetermined sequence, and manually operable means for controlling the feed of power to one of the engines. 50
10. In a system of the character described, the combination with a car having an exit door, steps and a trap door for normally covering the steps, of an engine for opening the exit door, an engine for opening the trap door, connections between said engines for conveying power from one engine to the other in predetermined sequence, manually operable means for controlling the feed of power to the engine of the exit door, and means included in the connections between the engines, and controlled by the proximity of a high level platform, for precluding the conveying of power to the operating engine of the trap door when the car is in proximity with such platform. 55
11. In a system of the character described, the combination with a car having an exit door, steps and a trap door for normally covering the steps, of a pneumatic engine for opening the exit door, a pneumatic engine for opening the trap door, a conduit leading from the engine of the exit door to the engine of the trap door and adapted to convey power to the latter engine from the former after the exit door engine has been operated to open the exit door, and a pneumatic valve for controlling the feed of power to the engine of the exit door. 60
12. In a system of the character described, the combination with a car having an exit door, steps and a trap door for normally covering the steps, of a pneumatic engine for opening the exit door, a pneumatic en- 65

gine for opening the trap door, a conduit leading from the engine of the exit door to the engine of the trap door and adapted to convey power to the latter engine from the former after the exit door engine has been operated to open the exit door, a pneumatic valve for controlling the feed of power to the engine of the exit door, and a valve included in said conduit, and controlled by the proximity of a high level platform, for precluding the communication of power to the engine of the trap door when the car is in proximity with such platform.

13. In a system of the character described, the combination with a car having an exit door, steps and a trap door for normally covering the steps, of a pneumatic engine for operating the exit door and embodying a cylinder with a piston therein, a pneumatic engine for operating the trap door, a conduit leading from one end of the cylinder of the trap door engine to a point inter-

mediate the ends of the cylinder of the exit door engine, a conduit leading from the end of the cylinder of the exit door engine to a point intermediate the ends of the cylinder of the trap door engine, a valve included in the latter conduit and which valve is adapted to preclude the flow of pressure through the conduit when the car is in proximity with a high level platform, a manually operable valve, conduits leading from said valve to the cylinders of both door engines, and cut off valves positioned in the last mentioned conduits, said cut off valves being operable to automatically seal their respective conduits when a passenger is on the trap door or steps.

In testimony whereof we have hereunto set our hands on this 29th day of April, 1925.

HAROLD ROWNTREE.
ROSCOE D. CONKLIN.
